SLOTTED STEAM DISTRIBUTOR TUBE

Joseph R. Gillis, Kalamazoo, Mich.; Esther M. Gillis, administratrix of said Joseph R. Gillis, deceased

Application February 2, 1953, Serial No. 334,667

6 Claims. (Cl. 299—132)

This invention relates to improvements in slotted steam distributor tube.

The principal objects of this invention are:

First, to provide structure for distributing or delivering steam in accurately controllable amounts and evenly distributed over a considerable longitudinal distance.

Second, to provide a steam distributor tube of substantial length with a slot of accurately controllable dimension extending the full length of the tube.

Third, to provide means for controlling the width of a slot extending longitudinally of a tube which tube is subject to high temperature.

Other objects and advantages of my invention will be apparent from a consideration of the following description and claims. The drawings, of which there is one sheet, illustrate a highly practical form of my distributor tube.

Fig. 1 is a vertical cross sectional view through a series of my distributor tubes mounted in a hood for drying ink.

Fig. 2 is an enlarged fragmentary longitudinal cross sectional view through one of the distributor tubes and taken along the plane of the line 2—2 in Fig. 3.

Fig. 3 is an enlarged fragmentary end elevational view of one of the distributor tubes and its connection to a manifold supply pipe.

My distributor tube is designed primarily for use in drying apparatus for ink on newly printed webs of paper such as is described and claimed in greater detail in my copending application for Methods and Apparatus for Drying Inks, Serial No. 701,851, filed October 7, 1946, now Patent No. 2,627,667, issued February 10, 1953. A more or less conventional view of the foregoing apparatus is illustrated in Fig. 1.

In Fig. 1 I have illustrated a chambered supporting platen 1 having a perforated upper surface 2 adapted to support a web 3 of freshly printed paper. A source of vacuum 4 opens to the platen and functions to hold the web flat against the perforated surface 2. A drying hood 5 positioned in closely spaced relationship over the web 3 is provided with means for introducing superheated steam in closely spaced and evenly distributed relationship over the surface of the web. A suction chamber 6 is positioned over the web at the rear end of the hood 5 where the web issues from the hood and is provided with a vacuum connection 7 for drawing off expanded steam and vaporized ink solvents. My above copending application emphasizes the desirability of discharging the steam closely adjacent to the surface of the web and in an evenly distributed manner over a substantial portion of the surface of the web.

The particular steam distributing apparatus illustrated includes a supply pipe 8 which opens to a superheater 9. The superheater 9 delivers to one or more manifolds 10 disposed longitudinally of the web and the manifold is connected to and supports a plurality of my steam distributor tubes 11. The manifold 10 is illustrated as being of circular cross section with the several distributor tubes 11 seated in notches in the underside of the manifold and sealed thereto as by welding at 12. Each tube has a port 13 opening into the manifold.

The tubes 11 are desirably of stainless steel material and are slotted longitudinally throughout their length as at 14. Overlapping segmental discs 15 are welded within the ends of the tubes to substantially close the same while permitting expansion and contraction of the walls of the tube as will be described.

The opposite side walls of the tube are transversely drilled or apertured at longitudinally spaced points to receive a series of transversely extending screws 16. The heads of the screws and the nuts 17 are seated against 5 spacer blocks 18 which have arcuate inner surfaces 19 seating snugly against the curved side walls of the tube.

I have found that the foregoing construction permits the adjustment of the several nuts 17 and screws 16 to accurately hold the side walls of the tube so that the 10 width of the slot 14 can be held within close limits even when the tubes become heated with the superheated steam passing therethrough. In actual use of the tubes in the drying apparatus referred to above, the width of the slot is adjusted to between .001 and .002 inch. This adjustment of the tubes and slots results in a delivery of a thin 15 continuous film of superheated steam completely along the length of the tube and transversely across the web 3.

While the tube has been described in connection with its use in an ink drying apparatus, it should be apparent 20 that the tube is capable of other uses wherever it is desired to distribute a thin controllable stream of a fluid medium. I therefore do not limit my invention to the particular application of the tube illustrated and reserve all uses and modifications of the tube as may fall within 25 the scope of the following claims.

Having thus described my invention, what I claim as new and desire to secure by Letters Patent is:

1. Steam distributing apparatus comprising, a supply 30 manifold, a plurality of distributor tubes connected to said manifold and extending transversely therefrom in spaced parallel relation, said tubes having continuous circularly curved walls with a slot formed longitudinally therein for the full length of the tubes, overlapping segmental end plates welded to the tubes within the ends of said tubes, a plurality of adjusting screws extending diametrically through the side walls of said tubes, and spacer blocks positioned around each end of said screws and having arcuate inner surfaces seating against the side walls of the tubes whereby the heads and nuts on the screws bear 35 against flat surfaces to accurately control the width of said slot by adjustment of the screws.

2. Steam distributing apparatus comprising, a supply 40 manifold, a plurality of distributor tubes connected to said manifold and extending transversely therefrom in spaced parallel relation, said tubes having continuous curved walls with a slot formed longitudinally therein for the full length of the tubes, overlapping segmental end plates welded to the tubes within the ends of said tubes, a plurality of adjusting screws extending diametrically through the side walls of said tubes, and spacer blocks positioned around each end of said screws and having arcuate inner surfaces seating against the side 45 walls of the tubes whereby the heads and nuts on the screws bear against flat surfaces to accurately control the width of said slot by adjustment of the screws.

3. Fluid distributing apparatus comprising, a supply 50 manifold, a plurality of distributor tubes connected to said manifold and extending therefrom in spaced parallel relation, said tubes having continuous curved walls and having a slot formed longitudinally therein for the full length of the tubes, means closing the ends of said tubes, a plurality of adjusting screws extending through the opposite side walls of said tubes on each side of the slots therein, and spacer blocks positioned around each end of said screws and having inner surfaces seating against the side 55 walls of the tubes whereby the heads and nuts on the screws bear against flat surfaces to accurately control the width of said slot by adjustment of the screws.

4. Fluid distributing apparatus comprising, a supply 60 manifold, a plurality of distributor tubes connected to said manifold and extending therefrom in spaced parallel relation, said tubes having curved walls and having a slot formed longitudinally therein for substantially the full length of the tubes, means closing the ends of said tubes, a plurality of adjusting screws extending through the opposite side walls of said tubes on each side of the slots therein, and spacer blocks positioned around each end of said screws and having inner surfaces seating against the side 65 walls of the tube whereby the heads and nuts on the

screws bear against flat surfaces to accurately control the width of said slot by adjustment of the screws.

5. A tube for distributing fluid mediums comprising, a cylindrical tube having an inlet in one portion of its wall, said tube being slotted longitudinally throughout its length, means including overlapping segmental plates secured in the ends of said tube to close the same, screws extending diametrically through said tube on opposite sides of said slot, and spacer blocks positioned around said screws and having arcuate inner surfaces engaging the outer surfaces of the tube whereby the heads and nuts on said screws bear against flat surfaces to control the width of said slot by adjustment of said screws.

6. A tube for distributing fluid mediums comprising, a cylindrical tube having an inlet in one portion of its wall, 15 said tube being slotted longitudinally substantially through-

10

5

out its length, means including overlapping segmental plates secured in the ends of said tube to close the same, screws extending through said tube on opposite sides of said slot, and spacer blocks positioned around said screws and having arcuate inner surfaces engaging the outer surfaces of the tube whereby the heads and nuts on said screws bear against flat surfaces to control the width of said slot by adjustment of said screws.
